HIGH-FREQUENCY AMPLIFIER

Filed Jan. 30, 1943

UNITED STATES PATENT OFFICE

2,429,760

HIGH-FREQUENCY AMPLIFIER

William Hotine, Watertown, Mass., assignor to
Federal Telephone and Radio Corporation,
Newark, N. J., a corporation of Delaware

Application January 30, 1943, Serial No. 474,173

7 Claims. (Cl. 315—39)

1

This invention relates to improvements in high frequency amplifiers, and more particularly to amplifiers of the type in which hollow metal cylinders forming part of a concentric line surround and enclose a vacuum tube to form a unitary amplifier structure and circuit.

An object of this invention is to provide an extremely stable amplifier of the type adapted to be used at ultra-high frequencies.

Another object of this invention is to provide a novel tuning arrangement for high frequency amplifiers.

Generally speaking, the invention is directed to the novel construction of a high frequency amplifier in which two concentric lines, one connected to the anode and the other to the cathode of an enclosed vacuum tube, are isolated from one another except through a common ground, and are both isolated from each other by the grid by a construction which separates the two lines; a subsidiary feature of this invention is directed to a novel arrangement for accurately tuning such an amplifier.

These and other features of the invention will become apparent from the following description of a preferred embodiment thereof, illustrated in the accompanying drawings in which:

Fig. 1 is a front elevation partly in section of the amplifier structure formed in accordance with the present invention; and

Fig. 2 is a simplified circuit diagram of the amplifier illustrated in Fig. 1.

As shown in the drawings, the amplifier consists primarily of a pair of hollow metal cylinders 10 and 12, which are positioned coaxially with their opposed ends spaced from one another. A vacuum tube 14, such as a triode is mounted in some suitable manner within the opposed ends of the cylinders. The vacuum tube 14 is preferably of the type having oppositely positioned anode and cathode elements 16 and 18 respectively, and a centrally positioned grid 20 having a generally radially extending terminal 24 passing through the surrounding glass envelope 22.

In accordance with the present invention, the metal cylinders 10 and 12 form the outer conductors of coaxial lines coupled in any suitable manner to the anode and cathode of the tube 14. Various coupling arrangements known to the art and which form no part of this invention per se may be used. In Fig. 1, I have indicated an inner metal conductor 26 which, with the outer metal cylinder 12 forms one coaxial line which will be coupled to the cathode 18. A similar inner

2

conductor (not shown) will be used in connection with the outer cylinder 10 and coupled to the anode 16.

The opposed ends of the outer cylinders 10 and 12 are respectively formed with outwardly extending radial flanges 28 and 30. About the end faces of these flanges are respectively positioned rings 32 and 34 of suitable insulating material such as polystyrene. Between the insulating rings 32 and 34 extends the radial grid terminal 24 and an outwardly extending grid lead 35. The two cylinders together with their flanged ends and the intermediate insulating rings, the grid terminal and the grid lead are drawn together by means of split insulating blocks 36 and 38 which surround the rear faces of the end flanges 28 and 30, and also the periphery of the insulating rings 32 and 34, and are drawn together by suitable means such as screws 40. The grid terminal 35, of which there may be one or more, extend radially outwardly from between these split blocks.

The whole amplifier unit is preferably mounted upon a grounded metal plate 42, the split insulating blocks 36 and 38, which may have a rectangular shape resting on the metal plate and supporting the center of the amplifier unit, the individual outer cylinders 10 and 12 being supported by means such as surrounding metal straps 44 which at the same time serve to electrically connect the surface of the cylinders with the ground plate 42.

Coupling may be made to the plate and cathode lines by the means illustrated at 46, 48 and 46', 48'. As shown in the right hand side of Fig. 1, the outer cylinder 12 may be formed with an opening surrounded by a projecting ring 46. Concentrically through the opening is positioned a rod 48, connected to the inner cylinder 26. The rod 46 and the ring 48 may, together, form a coaxial cable connector.

The structure so far described provides an amplifier circuit of the type indicated in Fig. 2. The cathode line is represented in Fig. 2 by the inductances 12 and 26 corresponding to the outer and inner cylinders of Fig. 1 while the plate line is indicated by the inductances 10 and 10', corresponding to the outer and inner cylinders on the other side. The grid will be further coupled to the outer cylinders 10 and 12 by capacitors C₁, C₂ which are formed by the grid terminal 24 as one common plate and the flanges 28 and 30, separated therefrom by the insulating rings 32 and 34, as the two outer plates. Since such capacitors will have a relatively poor dielectric con-

stant by reason of the thick rings 32 and 34, they will at high frequencies have some resistance as represented by R_1 and R_2 . By reason of the construction illustrated in Fig. 1 and the resulting circuit as shown in Fig. 2 it will be seen that the plate line is isolated from the cathode line by the grid, while the outer conductors 10 and 12 of the plate and cathode lines respectively are also isolated from one another by the grid flange, the only connection at high frequencies between them being through the relatively long inductive electrical path offered by straps 44 and the metal base 42. It has been found by test and experimentation that such an arrangement provides an amplifier which is externally stable at very high frequencies, for example, in the neighborhood of 600 megacycles.

Tuning of the aforescribed amplifier at ultra-high frequencies must of necessity be very accurate. In accordance with the present invention such accurate tuning is provided by means of a short circuiting ring 58 slidably mounted between the inner and outer conductors of the coaxial lines. Movement of the short circuiting ring 58 is effected through a pair of externally threaded arcuate segments 52 and 54, oppositely slidably mounted on the surface of the inner conductor 26. The arcuate segments 52 and 54 are attached in any suitable manner at one end to the short circuiting ring 58 while their other ends extend outwardly beyond the outer cylinder 12 and have threaded thereover a ring 56 provided with an outwardly extending radial flange 57. The flange 57 of the ring 56 is adapted to be positioned for rotation but against longitudinal movement in an internal annular groove 58 which may be built-up on the end of the outer cylinder 12 through a surrounding ring 59 having an inwardly extending flange for limiting the outward longitudinal movement of the flange 57 and defining one side of the annular groove 58. The ring 59 is mounted on the cylinder 12 through a spacing ring 60, the end of which may serve to form part of the boundary of the groove 58. A disc 62 positioned within the end of the cylinder 12 and having an end flange flush with the end of the spacing ring 60, forms the rest of the inner boundary of the annular groove 58. Means such as screws 64 will hold the rings 59 and 60, and disc 62 together and to the end of the cylinder 12. Threaded on the outer surface of the ring 56 are a pair of thin knurled discs 66 and 68. When these are locked together they will rotate the ring 56 which, because of its restraint in the lateral direction by the groove 58 will, through its threaded engagement cause longitudinal movement of the segments 52 and 54 through radial slots in disc 62, and thus a sliding adjustment of the short-circuiting ring 58. This arrangement permits a very fine control of the movement of the short-circuiting ring.

While the novel tuning arrangement illustrated has been described, particularly in connection with the cathode line 12, 26, a similar arrangement may be utilized for tuning the plate line, and similar parts have been indicated at 52', 54', 59', 66', and 68' at the left hand side of Fig. 1.

While I have described above the principles of my invention in connection with specific applications, it is to be clearly understood that this description is made only by way of example and not as a limitation on the scope of my invention as set forth in the objects and the accompanying claims.

I claim:

1. A high frequency amplifier comprising a pair of hollow metal cylinders each having a radially flanged end, a base, means coaxially mounting said cylinders on said base with their flanged ends opposed to one another, a vacuum tube mounted within the opposed ends of said cylinders, said tube having a terminal extending radially outwardly between the opposed cylinder flanges, a pair of insulating rings mounted on opposite sides of said terminal and against the respective end faces of the opposed cylinder flanges, a split insulating block surrounding the periphery and the rear faces of the flanges, clamping means drawing said split block together, and pulling said flanges toward one another with the insulating rings and tube terminals between, whereby said cylinders are held against longitudinal movement relatively to one another, a second cylinder mounted concentrically within one of said pair of hollow cylinders and forming a concentric line therewith, a slidable short-circuiting ring frictionally mounted between the two concentric cylinders, and adjusting means positioned on the end opposite the flanged end of the one cylinder for moving said short-circuiting ring.

2. An amplifier according to claim 1, in which said last means includes a pair of externally threaded arcuate slides positioned diametrically opposite on the inner cylinder and connected at one end to said short-circuiting ring, an internally threaded ring threadably engaging said slides at their other ends, said threaded ring having an outwardly extending radial flange on its inner end, means connected to the opposite end of the one outer cylinder forming an internal annular groove receiving said radial flange, whereby said threaded ring may be rotated but is restrained in longitudinal movement by said groove, and means for rotating said threaded ring for causing longitudinal sliding movement of said slides and short-circuiting ring through the engagement between said internally threaded ring and the externally threaded slides.

3. An amplifier according to claim 1, in which said base is a metal plate, and said cylinder mounting means comprises metal straps electrically connecting the outer surfaces of each cylinder to said plate and said surfaces to one another through said plate, in combination with an electrical ground connected to said plate.

4. A high frequency amplifier comprising a pair of hollow metal cylinders, each having a radially flanged end, a metal base, means coaxially mounting said cylinders on said base with their flanged ends opposed to one another and simultaneously electrically connecting the outer surfaces of said cylinders to said base, an electrical ground connected to said base, a vacuum tube mounted within the opposed ends of said cylinders, said tube having a terminal extending radially outwardly between the opposed cylinder flanges, a pair of insulating rings mounted on opposite sides of said terminal and against the respective end faces of the opposed cylinder flanges, a split insulating block surrounding the periphery and the rear faces of the flanges, and clamping means drawing said split blocks together, and pulling said flanges toward one another with the insulating rings and tube terminal between them, whereby said cylinders are held against longitudinal movement relatively to one another, and said terminal is capacitatively coupled to said cylinders through said insulating rings and flanges.

5. An amplifier according to claim 4, in combination with a second pair of cylinders, one positioned concentrically within each hollow cylinder and forming a concentric line therewith, and in which said vacuum tube includes a cathode connected to one inner cylinder, an anode connected to the other inner cylinder and a grid connected to said terminal.

6. A concentric line having an outer hollow metal cylinder surrounding a concentric metal cylinder, and a slidable short-circuiting ring intermediate the two cylinders, and means for adjusting the position of said ring, comprising a pair of externally threaded arcuate slides positioned diametrically opposite on the inner cylinder and connected at one end to said short-circuiting ring, an internally threaded ring threadably engaging said slides at their other end, said threaded ring having an outwardly extending threaded flange on its inner end, means connected to the adjacent end of the outer cylinder, forming an internal annular groove receiving said radial flange, whereby said threaded ring may be rotated but is restricted in longitudinal movement by said groove, and means for rotating said threaded ring for causing longitudinal

sliding movement of said slides and short-circuiting rings through the threaded engagement between said internally threaded ring and externally threaded slides.

5 7. A concentric line according to claim 6, in which said threaded ring is externally threaded, and said last means includes a pair of nuts threaded on said ring, said nuts being adapted to be locked against one another to prevent their relative rotation and cause rotation of said threaded ring.

10 WILLIAM HOTINE.
